UNITED STATES PATENT OFFICE.

JAMES R. CARDWELL, OF CHICAGO, ILLINOIS, ASSIGNOR TO UNION DRAFT GEAR COMPANY, OF CHICAGO, ILLINOIS, A CORPORATION OF ILLINOIS.

DRAFT-GEAR.

1,137,951.

Specification of Letters Patent.

Patented May 4, 1915.

Application filed August 23, 1909. Serial No. 514,172.

To all whom it may concern:

Be it known that I, JAMES R. CARDWELL, citizen of the United States, residing at Chicago, in the county of Cook and State of Illinois, have invented a certain new and useful Improvement in Draft-Gear, of which the following is a full, clear, concise, and exact description, reference being had to the accompanying drawings, forming a part of this specification.

My invention relates to friction draft gear employed in railway service, and has for its object the provision of a construction whereby a part of the friction-producing mechanism is brought into operation on light pulling and pushing strains, or during initial parts of heavy pulling and pushing strains, additional friction-producing elements being brought into operation when the pulling and pushing strains have been sufficiently increased. By means of my invention, lighter pulling and pushing strains will be resisted by the lighter friction and heavier pulling and pushing strains will be resisted by the heavier friction.

In the preferred embodiment of my invention, I use the type of draft gear disclosed in my Patents 819,266, dated May 1, 1906, and 861,636, dated July 30, 1907, but I do not wish to be limited to the type of draft gear shown in my said patents.

My invention will be well understood by a description of the preferred embodiment thereof, shown in the accompanying drawings, in which—

Figure 1 illustrates my improved draft gear in perspective, certain parts of the structure being broken away and other parts being shown in section, in order that certain details of construction may be revealed. Fig. 2 is a view in elevation of a two-part centrally disposed friction-producing element preferably entering into my improved construction. Fig. 3 is a plan view of a modification of the central friction member.

Like parts are indicated by similar characters of reference in both figures.

The center sills *a* may be of any well-known or suitable construction. The yoke *n* is attached to the shank *o* of the coupler bar. The follower members *g* and *h* carry elements that are preferably provided with friction surfaces that incline toward the center of the structure and which coöperate

with correspondingly inclined surfaces provided upon the friction blocks *g* *g* that are designed to travel transversely of the sills. The portions of the members *g* and *h* upon which the friction surfaces that engage with the blocks *g* *g* are provided, are preferably in the form of triangular blocks *g*¹ *h*¹ that are loose with respect to the balance of the members *g* and *h* and with respect to each other. I speak of the blocks *g*¹ *h*¹ as being portions of the members *g* and *h*, since the said blocks may remain in position in the absence of the laterally and longitudinally acting friction members, and as the invention is not to be limited to these movable blocks. These triangular blocks being loose, the particular elements of the members *g* and *h* that carry the same are provided with pockets *g*² *h*², into which the said triangular blocks are received. There are two triangular blocks for each element *g* and *h*, as indicated, which are associated with a supplemental friction-producing member divided transversely into two parts *g*¹ for the purpose to be stated, and which is provided with inclined friction surfaces at its ends that are adapted to engage adjacent friction surfaces upon each set of triangular friction blocks, these latter friction surfaces diverging away from the central longitudinal line of the gear. The friction blocks or members *g* *g* are provided with apertures extending transversely of the sills through the blocks, through which apertures the bolt *r* is passed, which bolt is surrounded with coil-springs *s* *s* that engage at their inner ends castings *t*, that are desirably separately formed with respect to the blocks *g* *g* for utility and convenience in assemblage and construction, the castings *t* or block mechanism passing through holes in the sills into engagement with the blocks *g* *g*. The outer ends of the bolt *r* are provided with caps *u* *u* that are preferably adjustable, whereby the tension of the springs *s* between said caps and the castings *t* may be regulated. The springs *s* *s*, acting through the castings *t* upon the blocks *g*, normally bring the said blocks in proximity and effect separation of the members *g* and *h*. When the member *h* is moved forward upon a sufficient pull upon the shank of the coupler and when the member *g* is moved rearwardly upon a sufficient push upon the shank of the coupler, the blocks *g*

are moved apart against the force of the springs s s , which are proportioned to offer the proper resistance to the relative motion between the members g and h for the purpose of the gearing, the springs s effecting the restoration of the parts to their normal positions when strain upon the shank of the coupler has been removed.

When a sufficiently great pulling or pushing strain is exerted, the triangular friction blocks g^1 h^1 first are effective to thrust the transversely movable friction blocks g apart against the force of the spring devices s , the friction then produced being limited to the outer faces of the triangular blocks and the inner sloping faces of the transversely movable blocks g . During the time that the production of friction is limited to these four places of contact, the blocks g^1 are moved toward each other and then are virtually one with the associate triangular blocks, during which time also it is very apparent that the triangular friction blocks of each set are not spread apart, so that no friction occurs between the end faces of the triangular friction blocks and the vertical end faces of the pocketed follower-plates g h . However, when the inner ends of the blocks g^1 are brought into contact, these blocks g^1 will, upon continued approach of the two sets of triangular blocks, wedge the blocks of each set apart, so that there will be increased friction due to the sliding of the vertical end faces of the triangular blocks upon the vertical end walls of the pocketed follower-plates g and h , and further friction will result as a consequence of the sliding engagement of the blocks g^1 with the inner inclined faces of the triangular blocks. Thus in the case of sufficiently light pulling and pushing strains, or in the case of the initial parts of heavier pushing and pulling strains, there are four places where friction is being produced, whereas on the heavier pulling and pushing strains, there are twelve places where friction is being produced. In this way lighter friction is produced where lighter friction only is required, and much increased friction is produced where much heavier friction is required. Moreover, it will be apparent that the opposition offered by the spring devices s s is less during the time the blocks g^1 are out of contact than is the case when said blocks g^1 are brought together, less opposition being needed from the spring devices on the lighter pulling and pushing strains and more opposition being needed from the spring devices during heavier pulling and pushing strains.

In Fig. 3 there is shown a modification of the structure in which the elements g^1 g^1 interengage, one thereof being formed with a tenon g^2 and the other with a complementary mortise g^3 . By this arrangement

these two blocks are more accurately kept in alignment. The combined length of the blocks g^1 g^1 is such that they serve as a limiting stop to prevent the over compression of the springs, the adjacent ends of the blocks meeting and their outer ends coming into engagement with the inner faces of the followers g h .

I have herein shown and particularly described the advantages that result from my invention when such invention is embodied in the type of draft gear illustrated in the drawing, but I do not wish to be limited in all embodiments of my invention to the adaptation thereof to the precise form of draft gear shown.

Having thus described my invention, I claim as new and desire to secure by Letters Patent:

1. A friction draft gear including relatively movable triangular friction blocks, a central longitudinally disposed friction element g^1 interposed between and frictionally engaging the same, and transversely movable friction blocks g between which the said friction element g^1 is disposed, which blocks g also have frictional engagement with the triangular blocks, the friction-producing element g^1 being divided transversely into two parts, and adapted to occupy a separated relation when the friction blocks g are closest together and being adapted for contact upon a predetermined separation of the friction blocks g .

2. In a draft gear, in combination, a pair of followers, a pair of aligned wedge-blocks located on the median line of the path of the followers; the combined length of such blocks determining the limit of the relatively approaching movement of the followers; a pair of opposed laterally movable wedging members engaging the wedge-blocks, and springs urging the wedging elements inward.

3. In a draft gear, in combination, a pair of opposed followers, a pair of wedge-blocks seated against the inner face of each follower, a pair of laterally movable wedge-blocks each engaging the outer lateral faces of one member of each pair of the first-mentioned wedge-blocks, means for yieldingly urging the second-named wedge-blocks inwardly, and a second pair of wedge-blocks respectively engaging the inner faces of the members of the two pairs of wedge-blocks first-named, the inner ends of the central wedge-blocks being normally out of contact.

4. In a draft rigging, the combination with the draw-bar, draw-bar yoke, center sills and stops, of followers, blocks, each having oppositely disposed wedging faces, a laterally extending rod, oppositely disposed wedge-shaped friction shoes slidably mounted thereon, springs pressing the shoes

inwardly, and limiting stops on each wedge adapted to contact each other, substantially as specified.

5. In a draft rigging, in combination; a yoke; center sills; stops; followers; wedges; friction shoes movable transversely of said sills and coöperating with the wedges; springs coöperating with said shoes; and a projection on one of the wedges extending toward the opposite wedge and adapted to engage the latter when the followers are

10 moved relatively toward each other, to thereby limit the amount of movement and compression of the springs, substantially as specified.

In witness whereof, I hereunto subscribe my name this twenty-first day of August A. D., 1909.

JAMES R. CARDWELL.
